UNITED STATES PATENT OFFICE.

JOHN B. ATWOOD, OF PITTSBURGH, PENNSYLVANIA.

RAIL-FASTENER.

1,155,698.

Specification of Letters Patent.

Patented Oct. 5, 1915.

Application filed December 17, 1912. Serial No. 737,354.

To all whom it may concern:

Be it known that I, JOHN B. Atwood, a citizen of the United States, and resident of Pittsburgh, in the county of Allegheny and 5 State of Pennsylvania, have invented a new and useful Improvement in Rail-Fasteners; and I do hereby declare the following to be a full, clear, and exact description thereof.

My invention relates to rail fasteners, and 10 is particularly concerned with a device of this character for securing railway rails on metal ties.

One object of the invention is to provide simple means by which the rail may be 15 quickly and securely fastened to the tie.

A further object is to provide means by 20 which the rail may be readily detached and by which new fasteners may be quickly substituted whenever necessary, while the rail maintains the same relative position with respect to the tie and with respect to the opposite rail.

A further object is to provide a fastener 25 whereby the rail will be clamped to the tie against both lateral and longitudinal movement thereon, and a further object is to provide means in which the driving home of a fastening pin or spike will have a tendency to impart a slight rotary movement to 30 the fastening member proper by which the latter will clamp the rail and tie more effectually.

With these objects in view, the invention 35 consists in a construction and arrangement of parts preferred embodiments of which are illustrated in the accompanying drawings, in which—

Figure 1 is a fragmentary view of a rail and tie showing one form of fastening means 40 applied thereto. Fig. 2 is a view transverse of the rail showing the tie and fastening means in elevation. Fig. 3 is a sectional view at right angles to that shown in Fig. 2, showing the rail in elevation. Fig. 4 is 45 a perspective view of one of the holding and clamping clips. Fig. 5 is an enlarged plan view of a clamping clip in rail holding position on the tie and before the fastening pin or spike is applied. Fig. 6 is a view 50 similar to Fig. 1, showing modified construction in which a clamping plate is employed in conjunction with clip member. Fig. 7 is a view on the line 7—7 Fig. 6; Fig. 8 is a view on the line 8—8 Fig. 6 and Fig. 9 is a view of 55 a modified form and arrangement of fastening pin.

Referring to Figs. 1 to 5, inclusive, 1 indicates the rail, 2 the metal tie. The tie may comprise the usual web and foot 3 and the bearing flanges 4, 4. In the embodiment of 60 the invention illustrated in Figs. 1 to 5, inclusive, the form of clip member employed comprises the body 5, having depending therefrom a tie engaging lug 6 properly spaced from the body portion to snugly engage the tie flange 4. The body portion and lug are provided with the apertures 7 and 8 respectively, substantially in line with each other, and preferably of oblong or oval form as shown to receive the fastening pin 9 of 65 like cross-section. The fastening pin is wedge shaped both on its broad and narrow sides so that it performs a wedging action both laterally and longitudinally of the tie as hereafter described.

From one side of the body portion projects a rail engaging lug 10 properly spaced from the bottom of the body of the clip as at 11 to snugly engage the rail flange and press it firmly against the tie. The tie flange 70 is provided with apertures 12 at the opposite sides of the web, as shown in Fig. 1, and properly positioned relatively to each other, so that when the clips are applied as shown and the fastening pins driven home the lateral movement of the clips with respect to the rail would normally have a tendency to twist the rail on the tie, but owing to the similar fastening device on the adjacent tie such twisting tendency will result in the 75 firm clamping of the rail to the tie.

The means for causing the clamping action of the clip member both on the tie and on the rail is clearly indicated in Fig. 5 wherein it will be seen that when the clip 80 member is assembled on the tie and its depending lug 6 engages the edge of the tie flange, and the shoulder of the rail holding lug 10 engages the flange of the rail, the edges 13 of the clip apertures 7 and 8 are 85 out of alignment with the edge 14 of the tie flange aperture so that when the universal wedge shaped pin 9 is driven home it will both draw the vertical wall 15 of the lug 6 firmly against the tie flange edge, and 90 will force the shoulder of the rail holding lug 10 firmly against the edge of the rail flange. By so arranging the edges of the clip apertures and the tie flange aperture respectively, and by employing a fastening 95 pin wedge shaped on all sides, the driving home of the pin simultaneously clamps the 100

clip and tie together and clamps the rail to the tie. Furthermore by reason of the staggered relation of the tie flange aperture 12 the tendency of the fastening of the clip is to give the rail a slight twisting or rotary motion with respect to the tie. This of course is counteracted by the fastening of the rail to the adjacent tie or ties and therefore results wholly in a firmer clamping action and one which not only prevents lateral movement of the rail with respect to the tie, but also effectually prevents creeping of the rail on the tie.

In the embodiment of the invention illustrated in Figs. 6 and 8 inclusive, I dispense with one of the clip members 5 heretofore described and employ a clamping plate 16 having at one side a rail flange engaging lug 17 and the tie flange engaging lug 18 and at the opposite side having a second tie flange engaging lug 19 and the extension 20 apertured as at 21 to receive the fastening pin 9. The tie flange and the clip member 12 are also provided with apertures as heretofore described. The tie and plate engaging lug 23 of the clip member is spaced more widely from the body of the clip member than in the form of clip heretofore described in order to embrace both the tie flange and clamping plate. In other respects the clip member is of the same construction as heretofore described and is provided with the rail engaging lug 24. The apertures in the clip member, the clamping plate and the tie flange respectively are out of alinement when so assembled and are so relatively arranged that when the tie and plate engaging lug 22 of the clip engages the edges of the tie flange and clamping plate the outer sides 25 of the clip apertures or those nearest the edge of the tie flange are out of alinement with and lie outside of the adjacent edge of the clamping plate aperture. Also the outer side edge of the tie flange aperture is slightly outside of the outer side edge of the clamping plate aperture so that as the wedge sided pin is driven home the clamping plate 16 is given a twisting or rotary motion with respect to the tie so that its lugs 18 and 19 firmly engage the opposite sides of the tie flange. The outer ends of the apertures in the clip member likewise lie slightly outside of the end of the apertures in the clamping plate and of the aperture in the tie flange, so that the driving home of the wedge pin clamps the rail flange firmly between the lug 24 of the clip and the lug 17 of the clamping plate. Thus by the described relative arrangement of lugs and apertures on the several members the mere act of driving home the wedge pin or spike serves both to clamp the clamping plate 16 and the tie flanges securely together and to clamp the rail securely to the clamping

plate. Moreover the twisting tendency of the clamping plate and the staggered relation of the clamping plate 17 and the clip lug 24 cause such lugs to exert a twisting tendency on the rail such as heretofore described whereby creeping of the rail with respect to the tie is effectually prevented. Moreover since the fastening pin passes through all three parts, namely, the clip, clamping plate and tie flange, these parts are securely held in fixed position with relation to each other, and neither can slide or creep on the other.

In order to insure the positive and powerful wedging action of the wedge shaped pin, the upper end of its shank adjacent the head is of a thickness slightly in excess of the area of the aperture in the clip, so that the head of the pin is not driven entirely home into contact with the clip. This serves the further purpose also of permitting the insertion of a claw bar beneath the head to withdraw the pin when necessary. The pin may be securely held in fastening position thereby providing its end with a transverse aperture through which a wedge shaped cotter pin 26 may be driven, or the extremity of the pin may be given a sharp blow to deflect it to one side and thus prevent its accidental withdrawal. This manner of fastening the pin may also be applied to the form of the device illustrated in the first five figures. The fastening pin may if desired be threaded at its outer end as shown in Fig. 9 and in such case may be passed up through the parts and secured by a suitable nut. As indicated at α Fig. 7, the rail may be insulated from the fastening means and from the tie by surrounding the flange with a layer of suitable insulating fabric covering all parts which would otherwise contact with the tie or fastening means. The rail may be likewise insulated in the structure shown in Fig. 2.

In the above specification, I have described the preferred embodiment of the invention, but it is to be understood that the latter may be varied in details and relative arrangements of parts within the scope of the appended claims.

What I claim is:

1. A rail fastener, comprising the combination with a tie, a clip member having a rail engaging lug and a tie engaging lug, the body and tie engaging lug of said clip member and said tie being apertured respectively, a pin to engage said apertures, said apertures being so relatively arranged that when the wedge pin is driven home the rail lug will be caused to firmly engage the rail flange and the tie lug will be caused to firmly engage the tie.

2. A rail fastener comprising in combination with a tie, a clip member having a rail flange engaging lug and having a tie

- engaging lug at right angles thereto, the body and the tie engaging member of said clip member being apertured and the tie being likewise apertured, a fastening pin 5 wedge shaped on all sides, said apertures being so arranged with reference to the lugs that when said pin is driven home the rail lug will be firmly clamped against the rail flange and the tie engaging lug will be firmly 10 clamped against the edge of the tie.
3. A rail fastener comprising in combination with a tie, a clip member having a rail flange engaging lug, and a tie engaging lug at right angles to each other, the body and tie engaging lug of said clip member being apertured and the tie being likewise apertured, a wedge shaped fastening pin, said 15 apertures being so arranged that when the parts are assembled with the lugs respectively snugly engaging the rail flange and tie, the outer side edges and outer end edges of the apertures of the clip member will lie outside of the corresponding edges of the tie aperture so that when the pin is 20 driven home the lugs of said clip member will be firmly clamped upon said rail flange and said tie respectively.
4. A rail fastener comprising the combination with a tie having a flange, a clip member having a rail engaging lug and a tie flange engaging lug, said clip member and said tie flange being apertured respectively, a wedge pin to engage said apertures, said 25 apertures being so relatively arranged that when the wedge pin is driven home the rail lug will be caused to firmly engage the rail flange and the tie lug will be caused to firmly engage the tie, and means for securing said pin in fastening position.
5. A rail fastener comprising in combination with a tie, a clamping plate having tie engaging lugs at opposite sides in staggered relation, a rail flange lug at one end and an aperture at the opposite end, a clip member 30 having a rail engaging lug, and a tie and clamping plate engaging lug, said clip member having substantially registering apertures in its body portion and its tie engaging lug, said tie having an aperture, a wedge 35 shaped fastening pin, the apertures in said clip member, clamping plate and tie being so relatively arranged when the parts are assembled that the driving home of the fastening pin through said apertures will cause a slight twisting movement of the clamping plate on the tie to cause its lugs to securely 40 engage the tie, the arrangement of the apertures being such as to cause the clamping plate lug and the rail clamping lug of the 45 clip member to firmly engage the opposite sides of the rail flange and to cause the tie engaging lug to firmly clamp the clamping plates and tie together.
6. A rail fastener comprising in combination with a tie, a clamping plate having lugs 50
- on opposite sides in staggered relation adapted to engage the opposite sides of the tie and having a rail flange engaging lug, a clip member having a rail flange engaging lug, said clip member, clamping plate and tie being apertured, a wedge shaped fastening pin adapted to engage said apertures when the parts are assembled, said apertures being so relatively arranged that the driving home of the fastening pin will cause a 55 twisting movement of the clamping plate on the tie whereby the lugs of said plate will firmly engage the tie, said driving home of the pin also simultaneously causing the rail engaging lugs of the plate and of the clip 60 respectively to simultaneously firmly clamp the rail, plate and tie together.
7. A rail fastener comprising in combination with a tie, a clamping plate having tie engaging lugs at opposite sides arranged in 65 staggered relation, said plate having also a rail flange engaging lug, a clip member having a lug adapted to engage the edges of the clamping plate and tie respectively, and a second lug adapted to engage the flange of 70 the rail on the opposite side from said rail engaging lug of the plate and in staggered relation thereto, said clip, plate and tie having apertures adapted to register substantially when the parts are assembled, a fastening pin wedge shaped on all sides, said 75 apertures being so arranged that when the fastening pin is driven home the clamping plate will be rotated slightly with respect to the tie to cause its lugs to firmly engage the tie at opposite sides and whereby the rail engaging lugs of the plate and clip member respectively may be caused to firmly 80 engage the rail flange at opposite sides with a tendency to impart a slight twisting movement to the rail and whereby the plate and tie engaging lug of the clip member will be caused at the same time to firmly engage the side edges of the plate and tie respectively, to hold the parts firmly in assembled position.
8. In a rail fastener the combination with a tie, of a clamping plate having lugs in staggered relation engaging the opposite sides of the tie, said plate also having a rail flange engaging lug, a clip member 90 adapted to clamp the rail on the opposite side of the rail from the rail engaging lug of the clamping plate, and means to simultaneously cause a twisting movement of said clamping plate relatively to said tie and rail to firmly clamp its lugs on said tie and rail respectively, and to cause said rail engaging lug of said clip member to firmly engage the 95 opposite sides of the rail.
9. A rail fastener, comprising the combination with a tie, a clip member having a rail engaging lug and a tie engaging lug, said clip member and said tie being apertured respectively, a wedge pin to engage 100
10. A rail fastener comprising in combination with a tie, a clamping plate having tie 105
11. A rail fastener comprising in combination with a tie, a clamping plate having tie 110
12. A rail fastener comprising in combination with a tie, a clamping plate having tie 115
13. A rail fastener comprising in combination with a tie, a clamping plate having tie 120
14. A rail fastener comprising in combination with a tie, a clamping plate having tie 125
15. A rail fastener comprising in combination with a tie, a clamping plate having tie 130

said apertures, said apertures being slightly out of alinement and so relatively arranged that when the wedge pin is driven home the rail lug will be caused to firmly engage 5 the rail flange and the tie lug will be caused to firmly engage the tie, and an insulating fabric interposed between the tie and rail, and between the rail and the clip.

10. A rail fastener comprising in combination with a tie, a clamping plate having tie engaging lugs at opposite sides in staggered relation, a rail flange lug at one end and an aperture at the opposite end, a clip member having a rail engaging lug, and a tie and 15 clamping plate engaging lug, said clip member having substantially registering apertures in its body portion and its tie engaging lug, said tie having an aperture, a wedge shaped fastening pin, the apertures in said 20 clip member clamping plate and tie being so relatively arranged when the parts are assembled that the driving home of the fastening pin through said apertures will cause a slight twisting movement of the clamping 25 plate on the tie to cause its lugs to securely engage the tie, the arrangement of the apertures being such as to cause the clamping plate lug and the rail clamping lug of the clip member to firmly engage the opposite 30 sides of the rail flange and to cause the tie engaging lug to firmly clamp the clamping plates and tie together, and an insulating fabric interposed between the tie and rail and between the rail and the clip.

35 11. A rail fastener comprising the combination with a tie, a clip member having a rail engaging lug and a tie engaging lug, said clip member and said tie being apertured respectively, a wedge pin having a 40 threaded end adapted to pass through said apertures, a securing nut to draw and hold

said pin in wedging position, said apertures being so relatively arranged that when the wedge pin is drawn to wedging position the rail lug will be caused to firmly engage the 45 rail flange and the tie lug will be caused to firmly engage the tie.

12. A rail fastener comprising in combination with a tie, a clamping plate having tie engaging lugs at opposite sides in staggered relation, a rail flange lug at one end and an aperture at the opposite end of said plate, a clip member having a rail engaging lug and a tie, a clamping plate engaging lug, said clip member having substantially 55 registering apertures in its body portion and its tie engaging lug, said tie having an aperture, a wedge shaped fastening pin having a threaded end adapted to pass through said apertures, a nut for said pin to draw 60 the latter into wedging position, the apertures in said clip member clamping plate and tie being so relatively arranged when the parts are assembled that the drawing 65 home of the fastening pin through said apertures will cause a slight twisting movement of the clamping plate on the tie to cause its lugs to securely engage the tie, the arrangement of the apertures being such also as to cause the clamping plate lug 70 and the rail clamping lug of the clip member to firmly engage the opposite sides of the rail flange, to cause the tie engaging lug to firmly clamp the clamping plate and tie together.

75 In testimony whereof, I the said JOHN B. Atwood have hereunto set my hand.

JOHN B. ATWOOD.
